UNITED STATES PATENT OFFICE.

EMIL WISMAR, OF LOS ANGELES, CALIFORNIA.

SPEINKLER.

1,036,765.

Specification of Letters Patent. Patented Aug. 27, 1912.

Application filed August 26, 1911. Serial No. 446,210.

To all whom it may concern:

Be it known that I, EMIL WISMAR, a citizen of the United States, residing at Los Angeles, in the county of Los Angeles, 5 and State of California, have invented new and useful Improvements in Sprinklers, of which the following is a specification.

This invention relates to improvements in 10 sprinklers and particularly to the class of sprinklers which are adapted for use in connection with hose or other pipe for the sprinkling or watering of lawns, gardens and the like.

It is an object of the invention to provide 15 a sprinkler which is provided with a suitable base in which is mounted a curved water distributing member, the force of the water passing through the same causing the same to rotate and properly spread the 20 water in distribution.

It is also an object of the invention to provide a sprinkler with a movable member adapted to be rotated by the action of the water passing through the same, which is 25 provided with an outlet opening or nozzle having an enlarged portion arranged to distribute the greatest quantity of water where it is to be thrown to the greatest distance.

In the accompanying drawing forming a 30 part of this specification, Figure 1 is a view partially in vertical central section and partially in elevation of the improved sprinkler as applied to the end of a hose. Fig. 2 is a top plan view of the sprinkler. Fig. 3 is 35 a horizontal sectional view taken upon the line 3—3 of Fig. 1, a portion of the supporting base of the device being broken away.

The details and features of the invention 40 will now be more particularly described reference being had to the said drawing in which—

5 indicates a hollow body portion and 6 a supporting base therefor while 7 indicates a movable water distributing member 45 mounted in said body portion. The body portion 5 is provided with vertically alined bearings 8 and 9 in its top and bottom walls in which the movable member 7 is 50 mounted. The said body portion is adapted upon one side to be fitted upon the end of a hose or pipe and for this purpose is formed with a screw threaded recess or socket 10. In the bottom of the socket an

opening 11 is provided communicating with 55 the interior of the said body portion 5. The said body portion is adapted to be supported upon the ground by any suitable base, the form shown in the drawing being the preferable one in which a broad ground 60 engaging ring is used, which is connected with the body portion 5 by a suitable number of radiating standards 12 usually formed integrally with the said body portion and the ring of the base 6, the said base 65 is thus sufficiently broad and ample for holding the sprinkler in upright position and also suitable for permitting the sprinkler to be moved from place to place.

The movable member 7 is preferably 70 made hollow throughout, the body portion thereof engaging the bearing 8 while the lower end extends to the lower wall of the casing 5 so as to abut upon the same and limit the downward movement of the member. 75 The said lower end is also provided with a reduced sleeve extension 13 rigidly secured in the end of said member 7 and adapted to engage the bearing 9. The said reduced sleeve portion is internally 80 threaded and a retaining screw 14 is inserted in the lower end thereof for holding the member 7 in position in its bearing. The screw also closes the sleeve at the lower end of said member. The screw 14 is so 85 arranged as to bear loosely against the under face of the body portion 5 so as to permit the member 7 to turn freely. The said movable member 7 extends a proper distance above the body portion 5 and its 90 upper end is curved and twisted into an approximately spiral form, the upper open end of the said member forming a discharge nozzle for the water. The portion of the member 7 which is within the chamber 95 formed in the body portion 5 of the device is provided with perforations 15 in its walls for admitting water to the interior of said movable member. The outer end or nozzle of the movable member 7 is preferably 100 formed with an enlarged portion 16 near its upper end, which is reduced toward its lower end forming a narrow discharge opening 17. The peculiar shaping of the nozzle is desirable since the water will 105 be discharged through said nozzle with the greatest quantity escaping at the top thereof, from which point water can be thrown

to the greatest distance. Toward the bottom of the nozzle the stream of water is reduced in volume where the water will fall short of that thrown from the upper 5 end of said nozzle.

The device is adapted to be applied to any ordinary hose or piping and the water entering the body portion 5 will pass through the apertures 15 into the movable 10 member 7. In forcing its way through the curved or spiral portion of the said member, the member will be rotated causing the water to be discharged from the nozzle at the upper end in a stream having a circular 15 movement about the sprinkler.

While the device has been shown as provided with a broad circular base, it will be understood that the body portion 2 of the device could be mounted upon a pin or 20 spike adapted to be stuck into the ground at any desired point, such as is in common

use upon ordinary sprinklers, within the spirit of the invention.

What I claim is:—

A sprinkler comprising a head adapted to 25 be connected with a water supply and having vertically alined bearings in its upper and lower walls, a rotatable distributing member engaging said bearings and having inlet apertures in its walls, the upper and 30 outer end thereof being bent spirally and having its discharge end formed with an opening enlarged at the top and flattened at the bottom.

In witness that I claim the foregoing I 35 have hereunto subscribed my name this 17th day of August, 1911.

EMIL WISMAR.
